UNITED STATES PATENT OFFICE.

CLARK HENDRICKS, OF RIVERSIDE, CALIFORNIA, ASSIGNOR TO JOHN JAHN, JR., OF RIVERSIDE, CALIFORNIA.

ROTARY ENGINE.

SPECIFICATION forming part of Letters Patent No. 764,465, dated July 5, 1904.

Application filed November 11, 1902. Serial No. 130,854. (No model.)

To all whom it may concern:

Be it known that I, CLARK HENDRICKS, a citizen of the United States of America, and a resident of Riverside, county of Riverside, State 5 of California, have invented certain new and useful Improvements in Rotary Engines, of which the following is a full, clear, and exact description, reference being had to the accompanying drawings, in which—

10 Figure 1 is a vertical sectional view of a motor or engine embodying the principle of my invention. Fig. 2 is a vertical sectional view taken centrally through the blades and the casing; and Fig. 3 is a side elevation of 15 the rotative parts, the shell or casing being removed.

The object of this invention is to provide an extremely simple, durable, and efficient 20 rotary engine which may be operated as a rotary pump or compressor, as more fully hereinafter set forth.

Generally the invention in its preferred form consists of a spherical casing in which is rotatably mounted a centrally arranged 25 sphere and between the sphere and casing a pair of approximately hemispherical pistons or shells, which nicely fit the spherical wall of the casing and the exterior of the central sphere and are arranged out of alignment with 30 each other at opposite sides of the sphere, so that their circular edges or plane surfaces shall bear against each other at one point in their circumference, and thereby form a fluid-chamber extending entirely around the casing 35 and tapering in opposite directions from a point opposite the point of contact of the edges, and a series of blades or partitions resting on the sphere and having their side edges engaging and working in slots in the said 40 faces or edges of the hemispherical pistons, and a suitable shaft or shafts centrally attached to the hemispherical pistons and journaled in the casing, whereby when a suitable 45 motive fluid is admitted into the peculiarly-shaped fluid-chamber the pressure of the fluid upon the blades and the inclined edges of the hemispherical pistons will impart a continuous rotary movement to the hemispherical pistons and carry with them the blades, thereby

transmitting said motion of the hemispherical 50 pistons to the shaft or shafts. When the device is used as a pump or an air-compressor, power is applied to one or both of said shafts, and as the parts rotate the liquid or air is drawn in at one side of the motor and forced 55 out at the opposite side or some other convenient point, as more fully hereinafter set forth.

Referring to the drawings by letters, *a* designates the spherical casing, which may be 60 suitably supported and may be constructed of two or more parts separably fastened together for convenience.

The letter *b* designates the two approximately hemispherical pistons inclosed within 65 the casing and having their convex surfaces nicely fitting the same, these pistons being attached centrally to shafts *c*, journaled in the casing. The shafts are journaled at an angle 70 to each other, so that their axial lines shall intersect at the center of the casing, whereby the hemispherical pistons shall lie at an angle to each other out of alignment. Supported within and nicely fitting the concavities in the said hemispherical pistons is the rotatable 75 sphere *d*, and resting loosely on this sphere are a series of radial segmental plates or partitions *b'*, whose outer edges are curved, so as to fit nicely against the interior of the casing 80 and whose inner edges are curved to nicely fit the surface of the sphere.

The adjacent faces or edges *d'* of the hemispherical pistons *b* are beveled off outwardly, so that they may fit and bear against each 85 other at one point in their circumference, this point being designated in the drawings by the letter *d*' and being equidistant from the two shafts *c*. The bevel-faces of the pistons may be provided with bevel-teeth or other intermeshing projections *e* in order that the two 90 pistons shall always rotate in unison. Coincident with each blade or partition the edge of each part *b* is provided with a radial slot *f*, into which one side edge of the blade extends and works as the pistons revolve, each of these 95 slots being of a width to freely fit the blades at their outer edges and being widened into a dovetail shape in the direction of their depth,

so that as the pistons revolve the blades may slide freely in and out of the slots and permit the bevel-faces d^2 to assume varying angles to the blades as the latter move away from or 5 approach the point of contact d' .

The partitions are slidable freely on the sphere, and to prevent them leaving the slots when at the wider points of separation of the pistons they are each slightly enlarged or provided with lateral projections at their side edges, as at b^2 . It is understood that packings and stuffing-boxes are to be used wherever found desirable.

If steam or other motive fluid be admitted 15 to the fluid-chamber at one side of the contact-point d' , the pressure against the partitions and the inclined faces of the pistons will cause the pistons to rotate, and as each partition passes the inlet-port the motive fluid will 20 be cut off from the preceding compartment and (when the fluid is of an expansive nature) allowed to work by expansion alone or (when of an in-expansive nature) by momentum until exhausted or forced out. It will be seen 25 that the fluid-chamber always remains of the same cubic area and formation, while the superficial pressure area of each of the partitions is constantly increasing until a point in the compartment midway between the partitions 30 is directly opposite the division-line d' , where the exhaust begins to take place. It will be further seen that the blades b' not only have a sliding and oscillating connection with the ball, but also have a sliding and pivotal 35 or oscillating connection with each of the pistons, so that they are entirely free to assume varying angles as the pistons rotate.

It is obvious that any suitable arrangement 40 of ports may be employed, one possible arrangement being illustrated in Fig. 2. By closing cocks 2 3 4 and opening cocks 5, 6, and 7 and adjusting the three-way valve 1 so that the motive fluid will enter the engine through pipe g the steam or other fluid will 45 enter the fluid-chamber just to the left of the contact-point d' and cause the pistons to revolve, the main exhaust taking place through valve 5 and the auxiliary exhaust through valves 6 and 7, these latter outlets being 50 simply to prevent compression of any of the motive fluid that may remain in the compartments after the rear partitions of each compartment passes the main exhaust-point, it being obvious that a free outlet must be provided for 55 each of the compartments during the period it is decreasing in size—that is, while it is moving toward the point d' . To reverse the motor, it is simply necessary to adjust valve 1 so as to direct the motive fluid through pipe 60 g' into the engine in the right side of the contact-point d' , close valves 5, 6, and 7, and open valves 2, 3, and 4.

To use the engine as a compressor or pump, 65 adjust valve 1 to admit fluid to pipe g , open valves 2, 3, and 4, close valves 5 and 6, and

apply power to one or both the shafts, whereupon the air or other fluid will be drawn in and compressed and forced out through valve 7.

It is of course understood that any other suitable arrangement of valves and ports may 70 be used to adapt the apparatus for use as either a reversible or non-reversible engine or compressor or pump and that therefore the arrangement as I have shown is only suggestive of the many arrangements I may finally 75 adopt. It is further obvious that the power may be taken off from or applied to one or both the shafts, though I have shown but one shaft provided with a band-wheel h . When but one shaft is to be used as a power-shaft, 80 the other one may simply be a stub-shaft stepped in a bearing formed in or secured to the interior wall of the casing and need not extend out through the same. It is obvious also that a great many other changes in the 85 construction may be made without departing from the spirit of the invention in the least, and I may state that I have in mind a number of modifications and minor changes that may be resorted to to render the apparatus particularly suitable to special uses and especially with regard to rendering it reversible 90 as well as convertible.

Having thus described my invention, what I claim, and desire to secure by Letters Patent, is—

1. In an apparatus of the class described, the combination of a spherical casing, provided with inlet and outlet ports, a pair of hemispherical pistons fitting within the casing and arranged at opposite sides thereof and having their edges or perimeters beveled outward and their inner faces provided with concavities, a sphere fitting and rotating in said concavities, a series of radial plates or partitions resting loosely on the sphere and working in coincident slots in said beveled perimeters or edges and provided with means for preventing their withdrawal from said slots, said perimeters or edges coming in contact at one 100 point in their circumference and being separated throughout the remainder of their circumference, thereby forming an oppositely-tapering fluid-chamber across which the blades or partitions extend and form compartments, and a power-shaft attached to one of said hemispherical pistons and extending out through the casing, for the purposes set forth.

2. In combination with a casing provided with suitable inlet and outlet ports, a pair of rotatable hemispherical pistons fitting within the casing and arranged at opposite sides thereof and at an angle to each other, an independent rotatable sphere fitting and working within concavities formed in the inner faces of said hemispherical pistons, and a series of rigid radial blades resting loosely on the sphere and extending across the annular space formed between the edges of said hemi- 115 120 125 130

5 spherical pistons and having a sliding and oscillating connection with both pistons and thereby dividing the annular space into fluid-compartments, and a power-shaft connected to one of said hemispherical pistons.

3. In combination with a casing, provided with suitable inlet and outlet ports, a pair of rotatable heads or pistons fitting within the casing at opposite sides thereof and having 10 their axes of rotation and their adjacent edges at an angle to each other, a rotatable part between said two heads at their centers, a series of rigid spaced radial blades resting loosely on the rotatable part and resting loosely on the sphere and extending across the annular space formed between the edges of said heads and dividing the same into fluid-compartments, and a rotatable power-shaft connected to one of said heads, substantially as set forth.

20 4. In combination with a casing provided with suitable inlet and outlet ports, a pair of rotatable heads or pistons fitting within the casing at opposite sides thereof and having their axes of rotation and their adjacent edges

25 at an angle to each other, a rotatable part between said two heads at their centers and rotatable therewith, a series of spaced radial blades extending across the oppositely-tapering annular space formed between the 30 edges of said heads and dividing the same into fluid-compartments, said blades extending into slots in the edges of said heads so as to have a sliding connection therewith, means for preventing said blades being withdrawn 35 from said slots and a power-shaft connected to at least one of said heads, substantially as set forth.

5. A rotary engine, the combination of 40 rotating heads having abutting conical faces, a rotatable part between said heads, a casing in which said heads rotate, radial slots in said heads, enlarged in the direction of their depth, a rigid blade fitting in each pair of opposite slots and serving to connect said heads 45 and resting loosely upon said rotatable part, and suitable ports in the casing between the heads.

6. In combination with a casing provided with suitable inlet and outlet ports, a pair of 50 rotatable pistons fitting within the casing at opposite sides thereof and having their axes of rotation and their adjacent edges at an angle to each other, a rotatable part between said two pistons at their centers, a series of radial blades extending across the oppositely-tapering annular space formed between the edges of said pistons and dividing said space into fluid-compartments, said blades extending into slots in the edges of said pistons and having a sliding connection therewith, the edges 55 of these blades lying in the slots being provided with lateral projections to prevent withdrawal from the slots, and a power-shaft connected to at least one of said pistons.

65 7. In a rotary engine, the combination of

a pair of rotatable heads having abutting conical faces, a casing in which said heads rotate, radial slots in said heads, a blade fitting within each pair of opposite slots and serving to connect said heads, means for preventing 70 the withdrawal of the blades from the slots, ports in said casing between the heads, and journals for said heads.

8. In a rotary engine, the combination of a casing provided with ports, a pair of rotatable disks or pistons having bearings at opposite sides of the casing, the adjacent faces and the axes of said pistons being set at an angle to each other, the adjacent faces abutting at one point on a radial line, thereby 75 forming an annular oppositely-tapering fluid-chamber, a rotatable part centrally between the pistons and a series of radial blades dividing said annular chamber into compartments, each blade having a movable connection with one of the pistons and a pivotal and sliding connection with the opposite piston, and a power-shaft connected with one of the disks.

9. In a rotary engine, the combination of 80 a casing provided with ports, a pair of rotating disks or pistons having bearings at opposite sides of the casing, the adjacent faces and the axes of said pistons being set at an angle to each other, the adjacent faces abutting at one 85 point on a radial line, thereby forming an annular oppositely-tapering fluid-chamber, a rotatable part centrally between the pistons and a series of radial blades dividing said annular chamber into compartments, said blades resting loosely on said rotatable part and having a pivotal and sliding connection with both pistons, and a power-shaft connected with at least 90 one of the pistons.

10. In an engine of the class described, the 105 combination, of a casing provided with inlet and exhaust ports, a pair of rotatable pistons journaled within the casing and having their adjacent faces and axes set at an angle to each other, said adjacent faces abutting on a radial line, a rotatable part arranged centrally between the pistons and having a rotatable bearing in at least one of the pistons, and a 110 series of rigid blades extending across the fluid-chamber formed between the pistons and resting loosely on the rotatable part and having a movable connection with each piston, said connection permitting the blades to 115 change their angular relation to the faces of the pistons as they rotate.

11. In an engine of the class described, the 120 combination, of a casing provided with inlet and exhaust ports, a pair of rotatable pistons journaled within the casing and having their adjacent faces and axes set at an angle to each 125 other, said adjacent faces abutting on a radial line, a rotatable part arranged centrally between the pistons and having a rotatable bearing in at least one of the pistons, and a series of rigid blades extending across the 130

fluid-chamber formed between the pistons and resting loosely on the rotatable part and having a movable connection with each piston, said connection permitting the blades to
5 change their angular relation to the faces of the pistons as they rotate, and positive means for causing the pistons to rotate in unison.

In testimony whereof I hereunto affix my signature, in the presence of two witnesses, this 6th day of November, 1902.

CLARK HENDRICKS.
